UNITED STATES PATENT OFFICE.

HENRY T. VAN DENBERGH, OF CHICAGO, ILLINOIS, ASSIGNOR TO THE PROGRESS NOVELTY MANUFACTURING COMPANY, OF SAME PLACE.

DESIGN FOR A CABINET.

SPECIFICATION forming part of Design No. 23,003, dated January 9, 1894.

Application filed October 27, 1893. Serial No. 489,319. Term of patent 3½ years.

To all whom it may concern:

Be it known that I, HENRY T. VAN DENBERGH, a citizen of the United States, and a resident of Chicago, in the county of Cook and State of Illinois, have invented and produced a new and original Design for Cabinets, of which the following is a specification, reference being had to the accompanying drawing, forming a part hereof.

This design relates to cabinets for exhibition, storage and other purposes, and has for its object to produce a novel and ornamental cabinet which shall present to the eye a distinguishing and characteristic appearance.

The leading feature of the design consists in a casing or body of oblong rectangular form in plan and front view and also in end elevation, the top of the casing being flat and having rounded edges projecting beyond the ends and front of the casing; the front of the casing being divided into three horizontal series of panels each of which panels is surrounded by a raised framing or beading, while at the ends of the casing are located open compartments inclosed between vertical side-pieces having curved ends and lying in a plane with the front of the cabinet.

The design is illustrated in the accompanying drawing in which the figure represents a perspective view of a cabinet embodying the design.

In the said drawing, A designates the body-portion or casing of the cabinet, this casing being of oblong rectangular form in plan and in front view and also in end elevation. The top of the cabinet is flat and has rounded edges B which project beyond the front and ends of the body-portion.

The front of the body-portion or casing A is divided into nine rectangular sections, disposed in three horizontal series or tiers each of which is composed of three of the sections. In each of these sections is located a rectangular panel which is surrounded by a raised rectangular beading or framing F, having 45 beveled or inclined inner edges F'.

At each end of the body-portion A are located five open compartments D arranged one above another and separated from each other by horizontal shelves D'; these compartments being inclosed laterally by two vertical side-pieces E. The lower ends of the side-pieces E are formed on a concave segment of a circle, while the upper ends of such side-pieces are each formed on an ogee curve. 55

What I claim is—

The design for a cabinet herein shown and described.

HENRY T. VAN DENBERGH.
